UNITED STATES PATENT OFFICE

EARL M. ROBINSON, OF WATERLOO, IOWA, ASSIGNOR TO RICHARD L. HALL, OF
WATERLOO, IOWA

ICE-CREAM-SHIPPING CASE

Application filed November 9, 1928. Serial No. 318,110.

My invention relates to improvements in ice cream shipping cases or the like, and the object of my improvements are these: First, to supply a heat non-conducting case for an inner removable container, the latter designed particularly for containing ice cream to be kept from melting while being shipped or stored, and the case being padded or otherwise constructed so as to be non-conducting for heat and having removable end caps also similarly made non-conducting, of which the lower also serves as a wear-cap to receive frictional wear during handling or transportation of the case, whereby when the lower cap is worn out, it may be readily and quickly replaced without any necessity for discarding the case; second, to provide said lower wear-cap with resiliently controlled means for removably clasping it upon the body of the case, and third, to otherwise improve the construction of the end-caps and body of the case for coaction and for proper assemblage, including means for releasably securing the upper cap upon the case.

These objects I have accomplished by the means which are hereinafter described and claimed, and which are illustrated in the accompanying drawings, in which Fig. 1 is a central vertical section of my improved shipping case including its end-caps, and Fig. 2 is an elevation of the same. Fig. 3 is an elevation of the upper end-cap alone. Fig. 4 is a bottom plan of the case body after removal of the lower end-cap. Fig. 5 is a detail plan view of the annularly connected coiled spring used within and for clasping the lower end-cap upon the body of the case, as unten-

My invention is not restricted to the precise construction and arrangement of parts herein shown and described, nor to the various details thereof, as the same may be modified or rearranged in various particulars without departing from the spirit and scope of my invention, one practical embodiment of which has been herein illustrated and described without attempting to show all of the various forms and modifications in which my invention might be embodied.

The numeral 7 denotes a hollow cylindrical

metal container for ice cream or other material to be kept at a desired temperature, said container being closed at the bottom, having an open top closed by a flanged removable cover closure 22. 1 is a hollow open ended cylindrical container whose spaced walls are closed at both ends to contain in the interspace heat non-conducting material padding 3, which also serves to yieldingly protect the container 7 from abrasions from without. As shown particularly in Figs. 2 and 4, flexible bands 4 and 5 are stitched along the sides of the case 1, ninety degrees apart, to cross the open bottom thereof and there to be secured together as by a rivet 6. A reinforcing flexible strip 8 is stitched around the case 1 near but spaced from its upper end and crossing the upper ends of the bands 4 and 5. Side loops 18 are endwise secured under the strip 8 to serve as handles for the case.

The top end-cap 9 is of the shape of an inverted cup and constructed with an inner wall part 19 which is cupped upwardly then directed outwardly to be end-connected to the side wall of the cap leaving an annular interspace between the said side wall and the side wall of the cup 19 to receive and fit the upper end of the case 1 closely, although there may be a small dead air space left at 21. The interspace of the cup part 19 and the top of the cap 1 is filled with like non-conducting padding 20 to that shown at 3. The bottom of the cupped part 19 may bear against the looped handle of the closure 22 to retain the latter in place.

The cap 9 may have its side wall split upwardly with overlapped angular flaps 10 and 11 shown in Fig. 3 secured adjustably together by a strap connection consisting of the members 12 and 13 fastened together in the usual way by means of a buckle 14. This permits an easy adjustable fitting of the side wall of the cap 9 over the upper end of the case 1 to be tightly mounted thereon.

Opposite the flaps 10 and 11, a vertically positioned strap 15 is riveted to the cap 9 and has its upper end eyed or looped to receive a metal end-ring 16 which serves as a finger-hold while removing the cap. The

strap 15 is secured adjustably by means of a buckle 17 to an underlying strap member, not shown, secured to the case 1.

The lower cap 23 is a wear-cap shaped as an upwardly opening cup with flexible textile wall and bottom parts connected together by stitching or other means, the side wall being a single thickness but having its upper margin 27 turned inwardly and stitched to provide a hollow annular receiving space for a contained elastic clasping member 28, the member 28 being preferably a helically coiled spring bent around into a ring with its terminations eyed at 29 and interlinked together. When the said marginal part of the lower cap is drawn over the lower part of the case 1, in the operation the annular spring 28 has to be tensioned to stretch it, then released to again contract to clasp the side wall of the cap 23 tightly upon the case, the flexible padded wall of which yields so that the spring hugs the case frictionally tightly and resists detachment by means of any ordinary force caused accidentally or due to handling. The cap 23 may be removed by stretching the spring enough to permit the slipping off of the cap. It will be understood that any other type of annular clasping-means may be employed instead of the annular spring 28, without departing from my invention.

The bottom part of the wear-cap 23 is a pad comprising the spaced walls 24 filled with like padding 25 to that hereinbefore described, the parts being end-connected by stitching to each other and to the side wall of the cap 23. The upper and lower walls 24 may be connected together by split pins or rivets 26, headed under the lower wall to serve as wear heads.

The wear-cap 23 is a non-conductor of heat also, and a yieldable pad to receive knocks without injury to the container 7. When the cap 23 is worn out by friction in use, it may be easily exchanged for a new cap, thus saving the case 1 for further use, which effects a great economy over types of such cases, which must be discarded when their integral lower parts are worn through.

It should be understood that the top cap fastenings 15-17 may be duplicated at the opposite side of the cap 9 if desired, to cooperate with the flap fasteners there, in securing the cap.

Having described my invention, what I claim as new, and desire to secure by Letters Patent, is:

1. A device of the character described, comprising in combination, a rigid hollow container, a flexible case surrounding said container, a cupped flexible wear-cap removably fitted upon the lower end part of the case, said wear-cap having its upper marginal part shaped and secured together to provide a hollow annular spring-case around the first-

mentioned case, and a helical spring mounted annularly in said spring-case with ends connected together to tensionally clasp the first-mentioned case on the first-mentioned case and container releasably.

2. A device of the character described, comprising in combination, a rigid hollow container, a flexible padded open end case around said container, a downwardly cupped top padded cap fitted and secured removably upon the upper end of said case, and an upwardly cupped bottom padded cap fitted upon the lower end of said case and containing annular elastic means for clasping it removably upon the case.

3. A device of the character described, comprising in combination, a rigid container, a flexibly padded outer casing therefor having open ends, flexibly padded caps removably fitted upon said open ends, the bottom cap being elastically clasped upon the casing, the upper cap having a split rim mounted around the casing with overlapped flaps, means for adjustably securing said flaps together under tension to hold the cap in place on the casing, and other fastening devices mounted respectively upon the cap and casing opposite said flaps and adjustably connected together to hold the cap in place against longitudinal separation from the casing while serving as a hinge connection when the flaps are separated and the cap swung open from the casing.

In testimony whereof I affix my signature.
